THREE DOOR BREAKFRONT OR THE LIKE

Joseph E. Adkinson, 3807 Leland St.,
Chevy Chase, Md. 20015

Filed Feb. 4, 1972, Ser. No. 223,828

Term of patent 14 years

Int. Cl. D6—04

U.S. Cl. D6—154

The single figure is a view in perspective of the three door breakfront showing my design.

The back of the three door breakfront is conventionally flat and the side not shown is identical to the side shown.

I claim:

The ornamental design for a three door breakfront or the like, substantially as shown and described.
